FLOOR VALVE

Elra F. Howe, 8730 S. Corcoran Road, Oaklawn, Ill.

Filed Dec. 14, 1960, Ser. No. 75,735

1 Claim. (Cl. 137—362)

This invention relates to a valve assembly, and more particularly to a valve assembly mounting in a floor drain.

A floor drain valve such as that shown and described in my U.S. Patent No. 2,869,727 may be installed in a floor drain opening, such as the end of tile or cast iron drain pipe or an internally threaded cast iron ferrule, for preventing the back flow of water and sewage, and the entrance of gases and bugs upwardly through the floor drain opening. Heretofore, installation of a floor valve has been complicated by the requirement of special techniques in the use of sealing materials such as lead and oakum, by the old drain opening having uneven or damaged portions in the end of the drain pipe, or the threads on the threaded ferrule being rusted or otherwise damaged.

It is, therefore, a new and improved primary feature of this invention to provide a rugged, effective assembly.

Another feature of the invention is the provision of a new and improved valve assembly including a device in which opposite ends of a resilient collar are seated in coaxially spaced seats adjustably mounted on a valve body for reducing the spacing between the seats to expand the collar into tight engagement with the inner surface of a drain opening. A further feature is the provision of such an adjustable seat mounting device in the form of a valve body having a tubular jacket with one end adjustably threaded received in a floor ring and with one seat on the tubular jacket and the other seat on the floor ring. A further feature is the provision in such a mounting device of means on the interior of the tubular jacket for turning the jacket in the threaded connection with the floor ring to adjust the spacing between the seats.

Further features and advantages will be readily apparent from the following description and drawings, in which:

FIGURE 1 is a vertical section of a valve assembly embodying the invention and installed in a floor drain pipe, with the valve closed;

FIGURE 2 is a fragmentary plan view thereof;

FIGURE 3 is a horizontal section taken substantially along the line 3—3 in FIGURE 1;

FIGURE 4 is a vertical section similar to that of FIGURE 1, but with the valve open;

FIGURE 5 is a fragmentary vertical section of a portion of the assembly prior to installation thereof in the floor drain opening;

FIGURE 6 is a fragmentary vertical section of the assembly installed in a floor drain threaded ferrule; and

FIGURE 7 is a broken, diametric section of a tool for use in installing the assembly in a floor drain opening.

The invention is, in brief, directed to a valve assembly in which a valve body includes a floor ring threadedly receiving a tubular jacket, and in which a resilient collar having opposite ends seated in seats on the jacket and ring, respectively, is deformed outwardly into engagement with the inner surface of a floor drain opening when the collar is longitudinally compressed by turning the jacket in the threaded connection with the ring for moving the seats toward each other. A valve is seated on the end of the tubular jacket opposite the ring, and has a valve stem extending longitudinally through the tubular jacket with an end adjacent the ring detachably receiving a valve actuating device which cooperates with the ring for opening the valve. By removing the actuating device, and a strainer basket, which may be provided, a tool may be

2

inserted into the tubular jacket for engaging protrusions extending inwardly from the tubular jacket for turning the jacket to move the seats toward or away from each other, thereby expanding or loosening the resilient collar.

5 Referring to the drawings, a valve assembly V, which is fully described in my aforementioned patent, comprises, in brief, a valve body 10 including a tubular jacket 11 having opposite ends, and a catch in the form of a floor ring 12 on one end of the tubular jacket. The floor ring 10 is preferably even with the floor level. A valve seat on the opposite end of the tubular jacket receives a movable valve in the form of a resilient ball 13 secured to a valve stem in the form of a threaded rod 14 extending longitudinally in the valve body 10. This stem has an end adjacent the floor ring 12 detachably and loosely receiving a socket portion of a valve actuator in the form of a strainer 17 adjustably positioned on the valve stem 14 by a nut 16, for positioning the valve actuator even with the floor ring 12 and the floor level. The valve 13 is maintained in a normally closed position by means of a compression spring 18 received between a nut 19 on the valve stem 14, for adjusting the closing force of the spring, and a guide bar 20 mounted in notches in the inner surface of the tubular jacket 11, and having a central aperture through which the valve stem 14 passes, for guiding the stem. The valve 13 is opened by depressing the valve actuator 15 and engaging it under an inwardly extending flange 21 on the floor ring 12.

In addition, if desired, a strainer basket 17 may be positioned on the valve stem 14 between the valve actuator 15 and the nut 16. The valve 13 is preferably a resilient hollow ball and is prevented from being squeezed into the tubular jacket 13 by a cupped washer 22, on the valve stem 14, which tightly engages the top of the ball. 30 Closing movement of the valve 13 may be limited by an abutment in the form of nuts 23 on the valve stem.

In the mounting device M an exterior thread 25 is provided on the outside of the tubular jacket 11 and is threadedly received in a cooperating thread in the floor ring 12 for longitudinal adjustment between a seat 27, in the form of an outwardly extending radial flange on the outer end of the floor ring 12, and a seat 28 on a seat ring 29 rotatably received on the tubular jacket 11 and maintained longitudinally positioned by engagement on an abutment in the form of an interiorly threaded abutment ring 30, threadedly received on the exterior threads 25 of the tubular jacket 11 for longitudinal, axial adjustment of the seat 28. Means in the form of a set screw 31 threadedly received in the ring 30 and engaging the tubular jacket 50 11 is provided for maintaining the ring fixed in adjusted position. Clamping means, in the form of a resilient cylindrical collar 35, preferably of rubber, or rubber impregnated with cord, or other suitable plastic material, encircles the valve body 10 and has opposite ends seated 55 respectively in the seat 27 and the seat 28. The collar 35 is arranged in such a manner as to be bulged outwardly and into tight frictional and sealing engagement with the inner side surface 36 of the open end of a cylindrical support, such as a drain pipe 37 which is suitably installed in a floor 38. The bulging of the resilient cylindrical collar 35 is directed outwardly because of the outer surface 32 of floor ring 12 which engages the inner surface of the resilient cylindrical collar 35, as illustrated 60 in FIGURE 5, for preventing inward deformation of the collar. 65

By removing the valve actuator 15 and the strainer basket 17, if used, from the valve body, means in the form of a pair of set screws 40, threadedly received in the tubular jacket 11 and extending into interior of the tubular jacket, may be engaged by notches 41 in a cylindrical body 42 of a tool 43 (FIGURE 7). Tool 43 is provided

with a handle 44 for turning the tubular jacket 11 in the ring 12 and moving the seat 28 toward the seat 27 to outwardly deform the resilient cylindrical collar 35 from the original flat side wall condition illustrated in FIGURE 5, to the distended condition illustrated in FIGURES 1 and 4 wherein it tightly engages the inner side surface 36 of the drain pipe 37.

FIGURE 6 illustrates the valve assembly secured in a cylindrical support such as a threaded ferrule 47, suitably installed in the floor 38, and having an interior threaded portion 48 engaged by the resilient cylindrical collar 35. It should be noted that the flange forming the seat 27 extends outwardly into contact with the top of the ferrule 47 which is recessed below the floor level.

The mounting device M facilitates mounting of the valve assembly V in any suitable floor drain opening by merely removing the valve actuator 15 and the strainer basket 17 and inserting the tool 43 into the tubular jacket 11 until the notches 41 engage the set screws 40, whereupon the tubular jacket 11 may be threadedly turned in the floor ring 12 to move the seat 28 toward the seat 27 without rotating the resilient cylindrical collar 35, thereby compressing the collar and expanding it into engagement with the inner surface of the drain pipe. By reversing the turning of the tubular jacket 11 the valve assembly may be removed from the drain pipe. In addition to providing a rugged and easily installed mounting arrangement for a valve assembly, leakage of water or sewage around the valve body 10 is prevented by the tight engagement of the resilient cylindrical collar 35 with the drain opening.

While I have shown and described certain embodiments of my invention, it is to be understood that it is capable of many modifications. Changes, therefore, in the construction and arrangement may be made without departing from the spirit and scope of the invention as disclosed in the appended claim.

I claim:

An assembly for selectively closing a generally cylindrical member, such as a drain opening through a floor, comprising: a valve body including an exteriorly threaded tubular jacket having opposite ends; a floor ring thread-

edly received on one of said ends for movement longitudinally of said jacket; a valve seat on the opposite end of said jacket; a valve cooperating with said valve seat; a valve stem connected with said valve and extending longitudinally within said valve body with an end adjacent said floor ring; a valve actuator releasably interlocked with said floor ring and detachably operatively engaging said stem end for opening said valve, said floor ring and said valve actuator being generally flush with each other in the closed position of the valve; a seat on said floor ring extending outwardly therefrom; an abutment comprising a ring threadedly received on said tubular jacket for adjustment longitudinally thereof; means for maintaining said abutment adjustably positioned on said tubular jacket; a seat comprising a ring rotatably encasing said jacket and freely seated on said abutment; a resilient cylindrical collar having side walls deformable outwardly for engaging the inner side surface of said cylindrical member, and opposite ends respectively seated in said seats; and means secured to and extending into said jacket for turning said jacket when said valve actuator is detached from said stem, whereby said collar is non-rotatably mounted on said floor ring and rotatable with respect to said jacket and is deformable into tight engagement with the inner side surface of said cylindrical member by turning said jacket to move said seats toward each other thereby compressing said collar.
